[57] CLAIM

The ornamental design for a retainer for eyeglasses, as
shown and described.

DESCRIPTION

FIG. 1 is an outer side elevational view of the first
component of a retainer for eyeglasses showing my new
design;

FIG. 2 is a rear end elevational view thereof;

FIG. 3 is an inner side elevational view thereof;

FIG. 4 is a front end elevational view thereof;

FIG. 5 is an inner side elevational view of the second
component thereof;

FIG. 6 is a front end elevational view of the second
component thereof;

FIG. 7 is an outer side elevational view of the second
component thereof;

FIG. 8 is a rear end elevational view of the second
component thereof;

FIG. 9 is a top plan view of the second component
thereof, the bottom plan view being a mirror image;

FIG. 10 is a top plan view of the first component
thereof, the bottom plan view being a mirror image;
and,

FIG. 11 is a top, left side and rear environmental per-
spective view of the two components as they would be
secured together, the portion of the figure shown in
broken lines representing the wearer's head and eye-
glasses and forming no part of the claimed design.
